UNITED STATES PATENT OFFICE.

CHARLES A. BARTLIFF, OF ST. LOUIS, MISSOURI.

APPARATUS FOR DRAWING BEER.

SPECIFICATION forming part of Letters Patent No. 710,739, dated October 7, 1902.

Application filed February 4, 1901. Serial No. 45,950. (No model.)

To all whom it may concern:

Be it known that I, CHARLES A. BARTLIFF, a citizen of the United States, residing at the city of St. Louis, in the State of Missouri, have 5 invented a certain new and useful Improvement in Apparatus for Drawing Beer, of which the following is a full, clear, and exact description, such as will enable others skilled in the art to which it appertains to make and use 10 the same, reference being had to the accompanying drawings, forming part of this specification, in which—

Figure 1 is a perspective view illustrating my improved system. Fig. 2 is a detail vertical sectional view showing one of the cooling-reservoirs. Fig. 3 is an elevational view of the top or cover of said reservoir. Fig. 4 is a bottom plan view of said top or cover. Fig. 5 is a top plan view of the reservoir; and 20 Fig. 6 is a sectional view through a cooling-chamber, showing several cooling-reservoirs in position therein.

This invention relates to a new and useful improvement in a system of drawing beer, 25 the object being to utilize a system of storage-reservoirs, whereby the beer on draft may be chilled or cooled in its passage from the keg to the spigot.

With these objects in view the invention 30 consists in the construction, arrangement, and combination of the several parts, all as will hereinafter be described and afterward pointed out in the claims.

In the drawings, Fig. 1 shows my improved 35 system arranged in position, the kegs of beer or source of supply being in what we will designate as the "cellar" or "lower compartment," having a pressure-reservoir connected therewith, while the pipes leading 40 from said kegs enter a cooling-chamber containing a series of reservoirs from which the beer is drawn.

A indicates the kegs or barrels containing 45 the beer, from which lead pipes B to a cooling-chamber C. These pipes have appropriate cocks and manually-operable connections, such as are usually employed. The pipe B entering the cooling-chamber is connected to a reservoir D. There are a series of these 50 reservoirs in the cooling-chamber, and as they are practically identical in construction I will describe but one. This reservoir

is preferably made of glass in the form of a jar having a threaded neck for receiving a coupling-collar E. The side walls of the jar 55 at the bottom are provided with projections d, designed to fit in recesses in the bottom of the reservoir C, whereby when the jar is in position in said cooling-chamber it is prevented from being turned. 60

F indicates a cap or cover for the reservoir, which cover is preferably made as a casting, between which and the top of the reservoir is arranged a suitable gasket f for well-understood purposes. The coupling-collar E is provided with an inturned flange at its upper edge extending over the margin of the cap F, whereby when said coupling-collar is screwed home it clamps the cap in position and seals the reservoir. For ease of manipulation this 70 coupling-collar is preferably provided with handles e. Cap F is provided with a screw-threaded boss f', upon which is received a coupling-collar f'', said coupling-collar securing in position the end of the pipe B. A gasket is arranged between the end of pipe B and the boss f' for well-understood purposes. f³ indicates a boss similar in all respects to the boss f', said boss f³ also receiving a coupling-collar f⁴, to which coupling-collar is secured a nipple f⁵, said nipple receiving a tube 75 f⁶, which tube connects with the boss f' of the next adjacent reservoir. The cap F is also provided with a nipple f⁷, substantially in alignment with the boss f³, to which nipple 80 f⁷ is secured a glass tube f⁸ by means of some appropriate connection—as, for instance, a short section of rubber tube f⁹. This glass tube f⁸ extends to the bottom of the reservoir and forms part of the delivery-pipe 90 from said reservoir. These reservoirs are connected together in series, the delivery-pipe from one terminating at the cap of the other, &c. The delivery-pipe of the last reservoir in the series connects with a spigot 95 f¹⁰, extending outside the cooling-chamber, as shown in Fig. 1. In order to prevent the cap F from turning on the reservoir, I provide lugs d' in the neck of the reservoir, which lugs fit in corresponding recesses in the under 100 flange of the cap F.

G indicates a reservoir preferably arranged in juxtaposition to the source of beer-supply, which reservoir G is in the form of a tank

and contains compressed gas. From this tank leads a pipe *g*, preferably provided with a pressure-gage and suitable cocks, said pipe connecting with a fitting through which said pipe B passes in its entrance into the kegs.

The operation of my improved system is as follows: The reservoirs being connected as shown and the beer admitted thereto, the beer will flow into the reservoirs, practically filling them. The reservoirs being surrounded by ice will enable the beer to be readily chilled or cooled, and as the beer is drawn from the reservoir nearest the spigot a supply of fresh cold beer immediately flows into said reservoir from those reservoirs connected therewith. It will be noticed that the intake-pipes of all the reservoirs terminate at the cap or cover, while the outlet-pipes start from the bottom of the reservoir. By this construction the liquid is allowed to flow from one reservoir to the other, keeping all of them filled as long as the supply of beer in the keg equals the demands upon the spigot. However, when the beer is exhausted from the keg the pressure from the tank *G* is then exerted directly upon the surface of the beer in the last reservoir, forcing said beer out through the discharge-pipe according to the demands upon the spigot, and when the beer is exhausted from said last reservoir the pressure from the tank *G* is direct upon the surface of the beer in the next reservoir. The tank *G* is charged to a pressure of, say, one thousand five hundred pounds to the square inch, which pressure is reduced by suitable means arranged in the length of pipe *g* and interposed between said tank *G* and the kegs to, say, five pounds pressure to the square inch. Hence it will be seen that the charge of gas contained in said tank *G* is sufficient to exhaust quite a large number of kegs of their contents.

By constructing the reservoirs and their pipes of glass tubing where possible, thus reducing the iron surface which might contact with the beer to the smallest area, I am enabled to keep the apparatus in a cleanly condition with a minimum amount of labor. All couplings, &c., are preferably what is known as "union-couplings," so that they may be readily coupled and uncoupled.

Having thus described my invention, what

I claim, and desire to secure by Letters Patent, is—

1. The combination with a reservoir, of a removable cover for the reservoir comprising a cap *F* resting upon the upper edge of the reservoir, means for locking the cap against independent rotation, clamping means for holding the cap in place, inlet and outlet openings in the cap, an outwardly-extending boss adjacent the inlet-opening adapted to be coupled with a suitable supply, a corresponding boss adjacent the outlet-opening adapted to be coupled with a suitable discharge, a third boss extending inwardly from the cap in alignment with the outlet, and a tube coupled to said third boss and projecting downwardly to a point near the bottom of the reservoir, substantially as described. 70

2. The combination with a receptacle, of a cap for closing the top of the same, means for preventing independent movement of said cap, a gasket under said cap, a coupling-collar for clamping said cap on the gasket, 75 threaded bosses projecting up from the cap, pipes detachably connected to said bosses, and a boss on the under side of the cap in line with one of the first-mentioned bosses, and a pipe depending from said downwardly-projecting boss; substantially as described.

3. In combination substantially as described, a receptacle, a series of reservoirs seated in said receptacle, removable caps fitting the mouths of the reservoirs, rotary 85 clamps movable independently of the caps for retaining the same in place, means for preventing independent rotation of the reservoirs in their seats, auxiliary means for preventing independent rotation of the caps relative to the reservoirs, inlets and outlets in the caps, communications between the adjacent caps, and a source of supply and a discharge respectively coupled with the end reservoirs of the series, substantially as described. 90 95

In testimony whereof I hereunto affix my signature, in the presence of two witnesses, this 28th day of January, 1901.

CHARLES A. BARTLIFF.
